UNITED STATES PATENT OFFICE.

WILLIAM F. HALL, JR., OF CASTLE POINT, NEW YORK.

SAFETY RAZOR.

Application filed October 17, 1928. Serial No. 312,940.

This invention relates to safety razors of the type wherein the razor blades are provided by a continuous flexible steel band.

The invention seeks to provide an inexpensive structure, efficient in service and effective and convenient in operation.

The invention consists of the features hereinafter pointed out and set forth in the claims.

10 In the accompanying drawings forming part of this specification, and in which like reference numerals designate corresponding parts,

Fig. 1 is a section of the razor on the line 15 1—1 of Fig. 2.

Fig. 2 is a section on the line 2—2 of Fig. 1.

Fig. 3 is a plan view of the head of the razor partly in section and partly broken 20 away.

Fig. 4 is a detail showing the steel band which provides the cutting edge.

Figure 5 is a cross sectional view of the parts by which the cutting edge of the steel 25 band is sharpened and preserved.

Referring now to the drawings, the head of the razor 1 and the handle 2 are constructed in the form of a hollow casing, preferably of light sheet steel. The top 30 plate 3 of the head is provided with teeth 4 which teeth provide the usual guard for the cutting edge. The plate 3 which extends across the head defines the cutting position and provides a support for that section of 35 the cutting band which, for the time being, is in cutting position. The cutting band 5 is provided with perforations 6. It extends across and immediately above the support 3, thence down through one side of the handle and up through the other side thereof.

40 At the bottom of the handle, it passes around a drum 7 provided with teeth 8 which engage the perforations 6 of the band 5. This drum is fixed on a shaft 9 mounted 45 in the opposite sides of the handle, one end of which projects outside the casing and has pivotally fixed thereon a ring handle 10. Also fixed on the shaft 9 is a toothed gear 11 provided with a spring pawl 12 whereby 50 rotation of the drum is permitted in only one direction. Formed in the handle at its lower end is a recess 13 in which the ring 10 may be folded when not in use. The head of the razor is provided with an inset 55 14 to facilitate the action of the cutting

edge when in use. Projecting through a central aperture 22 in the supporting plate 3 is a plate 15 mounted on a pivot 16. The forward edge of this plate 15 bears against the rear edge of the band 5 on that section 60 of the band in cutting position when the same is in active use. It may be adjusted by a thumb screw 17 which projects on the outside of the head. The abutment 15 acts to push forward that section of the band which 65 is in cutting position so that its cutting edge may be always kept forward in its most advantageous cutting position and may thus compensate for any possible decrease in the width of the band due to sharpening. It 70 also acts to resist back thrust on said section of the band when the same is in active use. Immediately above the supporting plate 3 is a clamp plate 18 secured in place by a hinge 19 provided with a spring 20 75 which acts to press the clamp down against the steel band so as to hold it firmly against the supporting plate 3. 21 is a spring tension device over which the band passes, the same acting to keep the band sufficiently taut. 80

Within the handle and secured thereto is a pair of pads 23 and 24 which closely embrace the band 5 on either side. These pads are preferably well oiled before being secured in place and serve the purpose of 85 cleaning and oiling the band as it passes between them so as to keep the band free from rust. Also within the handle and opposite the pads 23 and 24 is a pair of sharpening devices 25 and 26 which closely embrace the band 5 on either side thereof. They may be made of stone, leather or other material; and serve to sharpen the cutting edge of the band as it passes therethrough.

Figure 5 illustrates the manner in which 90 the devices 25 and 26 engage the edge of the band 5 and keep it sharp.

The part 26 preferably bears against the band with a yielding pressure. As shown in the drawings, this is provided for by securing the part 26 to a metal plate 27 which has a to and fro movement on supporting pins 28 and 29 passing through slots in the ends of the plate 27. Coiled springs 30 and 31 are interposed between the plate 27 and the back plate 32 fixed within the handle. The band is guided through the head by small rolls or pins 21, 34, 35, 36 and 37 fixed therein. The band 5 also passes between a pair of pads 38 and 39 mounted at 110

one side of the head, and a pair of pads 40 and 41 mounted on the opposite side of the head. These pads are preferably made of felt or other suitable material and serve the purpose of wiping the band as it passes therethrough and removing oil or moisture from the band.

By providing the razor with the casing 1 and handle 2 with the drum 7 in the outer 10 or far end of the handle, I am enabled to use a band 5 of greater length and at the same time have sufficient space for the sharpening devices 25 and 26, the oiling pads 23 and 24 and the wiping pads 38, 39, 40 15 and 41. At the same time the razor is not made bulky, but it can be constructed in relatively small sizes and be neat and compact in design, with the band 5 large enough for 20 long service and the other parts capable of active cooperation with great efficiency to keep the edge of the band sharpened and the whole outside surface of the band lubricated and wiped.

I claim:

25 1. In a safety razor having a head with a guard and a handle for the head, the combination of an endless steel band having a continuous cutting edge and perforated throughout its length, the head being shaped 30 to expose a portion of said edge adjacent the guard, with a toothed rotatable drum over which the band passes disposed at the outer end of the handle, the teeth of the drum engaging the perforations in the band 35 to adjust different sections of the band consecutively into cutting position.

2. In a safety razor having a head with a guard and a handle for the head, the combination of an endless steel band having a continuous cutting edge and perforated throughout its length with a toothed rotatable drum over which the band passes disposed at the outer end of the handle, the teeth of the drum engaging the perforations 40 in the band to adjust different sections of the band consecutively into cutting position, and a sharpening device in the handle over which the band passes.

3. In a safety razor having a head with 50 a guard and a handle for the head, the combination of an endless steel band having a continuous cutting edge and perforated throughout its length with a toothed rotatable drum over which the band passes 55 disposed at the outer end of the handle, the teeth of the drum engaging the perforations in the band to adjust different sections of the band consecutively into cutting position, and a sharpening device in the handle comprising two elements between which the band passes as it is driven by said drum.

4. In a safety razor having a head with a guard and a handle for the head, the combination of an endless steel band having 60 a continuous cutting edge and perforated

throughout its length with a toothed rotatable drum, positioned in the outer end of the handle, over which the band passes, the teeth of the drum engaging the perforations in the band to adjust different sections 70 of the band consecutively into cutting position, and a sharpening device, positioned in the handle between said drum and the razor head, comprising two elements between which the band passes as it is driven by 75 said drum.

5. In a razor, the combination of an endless steel band having a continuous cutting edge and perforated throughout its length with a toothed rotatable drum over which 80 the band passes, the teeth of the drum engaging the perforations in the band to adjust different sections of the band consecutively into cutting position, and a pivoted adjustable abutment in the head of the razor 85 bearing against that section of the band in cutting position when the same is in active use.

6. In a safety razor having a head providing a cutting position, the combination of 90 a steel band having a continuous cutting edge adapted to have its various sections moved consecutively into cutting position, a toothed support in the head for the band, a clamp to hold the band down on said support and a pivoted adjustable abutment in the head bearing against that section of the band in cutting position when the same is in active use.

7. In a safety razor, the combination of a 100 hollow case providing a head and a handle, a toothed support in the head, a perforated endless steel band having a continuous cutting edge and adapted to have its various sections moved consecutively over said 105 toothed support, a toothed drum mounted at the outer end of the handle over which said band passes, said drum being rotatable to bring succeeding sections of the band over said toothed support and so as to occupy the cutting position thereon, and a clamp to hold the band down on said support.

8. In a safety razor, the combination of a 110 hollow case providing a head and a handle, a toothed support in the head, a perforated endless steel band having a continuous cutting edge and adapted to have its various sections moved consecutively over said 115 toothed support, a toothed drum mounted in the outer end of the handle over which said band passes, said drum being rotatable to bring succeeding sections of the band over said toothed support and so as to occupy the cutting position thereon, a clamp 120 to hold the band down on said support, and a sharpening device mounted in the handle over which the band passes.

9. In a safety razor, the combination of a 125 hollow case providing a head and a handle,

a toothed support in the head, a perforated endless steel band having a continuous cutting edge and adapted to have its various sections moved consecutively over said toothed support, a toothed drum mounted in the lower end of the handle over which said band passes, said drum being rotatable to bring succeeding sections of the band over said toothed support and so as to occupy the cutting position thereon, a clamp to hold the band down on said support, an adjustable abutment in the head bearing against that section of the band in cutting position when the same is in use, and a sharpening device mounted in the handle 15 over which the band passes.

10. In a safety razor having a head with a guard, and a handle for the head, the combination of a band blade extending through said head and handle means to 20 move said blade to expose a portion of its edge adjacent the guard, means to hold the exposed edge of the blade in cutting position and sharpening means for the cutting edge of said blade mounted in the handle. 25

In testimony whereof I have affixed by signature to this specification.

WILLIAM F. HALL, JR.
